UNITED STATES PATENT OFFICE.

FRANK F. BURTON, OF MOUNT CARMEL, CONNECTICUT, ASSIGNOR TO WINCHESTER REPEATING ARMS CO., OF NEW HAVEN, CONNECTICUT, A CORPORATION.

BOLT-ACTION GUN.

1,324,493.

Specification of Letters Patent.

Patented Dec. 9, 1919.

Application filed August 9, 1919. Serial No. 316,391.

To all whom it may concern:

Be it known that I, FRANK F. BURTON, a citizen of the United States, residing at Mount Carmel, in the county of New Haven and State of Connecticut, have invented a new and useful Improvement in Bolt-Action Guns, and do hereby declare the following, when taken in connection with the accompanying drawings and the characters of reference marked thereon, to be a full, clear, and exact description of the same, and which said drawings constitute part of this application, and represent, in

Figure 1 a broken plan view of a bolt-action gun constructed in accordance with my invention.

Fig. 2 a right hand side view thereof.

Fig. 3 a view of the gun in partial vertical central longitudinal section on the line 20 3—3 of Fig. 1, showing the gun as fired.

Fig. 4 a corresponding view showing the gun as cocked.

Fig. 5 a corresponding view showing the gun with its firing-pin retracted and locked by the safety.

Fig. 6 a broken view in left hand elevation showing the rear end of the receiver of the gun with the safety in its upright and operative position, the handle and bolt being removed.

Fig. 7 a view in transverse section on the line 7—7 of Fig. 1, the safety being shown in its operative position and the bolt-handle being broken away.

Fig. 8 a corresponding view with the safety in its inoperative position.

Fig. 9 a detached view in side elevation of the safety, shown on an enlarged scale.

Fig. 10 a view thereof in rear elevation.

Fig. 11 a view thereof in front elevation.

My invention relates to bolt-action guns, and more particularly to improved safety devices therefor, the object being to produce a simple, compact, durable and reliable mechanism in which a safety axially mounted in the receiver has the two-fold function of locking the firing-pin in its retracted position, and of locking the bolt-handle in its closed position.

With these ends in view, my invention consists in a bolt-action gun in which a

safety axially mounted in the receiver operates as a cam to retract the firing-pin from engagement with the nose of the sear.

My invention further consists in a bolt-action gun in which a safety axially mounted in the receiver, cams the firing-pin out of engagement with the nose of the sear and at the same time locks the bolt-handle in its closed position.

My invention further consists in a bolt-action gun having certain details of construction as will be hereinafter described and pointed out in the claims.

In carrying out my invention as herein shown, my improved axially mounted safety comprises a wing-like handle 8 radially offsetting from a substantially circular head 9 having a central opening 10 receiving the rear end 11 of a rock-shaft 12 to which the said head is secured by a transverse pin 13. The rearward face of the head is shaped to form a cam 14 which co-acts with the adjacent portion of the forward face of an annular flange 15 formed at the forward end 70 of a head 16 on the rear end of the firing-pin 17 and provided for manually retracting the same. The rock-shaft 12 aforesaid is made in one piece and comprises two trunnions 18 and 19 separated by a transverse 75 segmental clearance-slot 20 which corresponds in width to the hub 21 of the bolt-handle 22, the trunnions 18 and 19 having bearing in a suitable bearing-hole formed in the left hand wall of the receiver 23 80 segmental clearance-slot 20 which corresponds in width to the hub 21 of the bolt-handle 22, the trunnions 18 and 19 having bearing in a suitable bearing-hole formed in the left hand wall of the receiver 23 85 parallel with the axis thereof, whereby the safety is axially mounted therein. Interposed between the head 9 and the trunnion 18 of the rock-shaft, is an annular positioning-shoulder 24 having beveled positioning-recesses 25 and 26 connected by a shallow-guide-groove 27, the said recesses and groove receiving a spring-actuated plunger 28 located in the receiver and serving when entered into the said recesses to hold the 90 safety in its operative or inoperative or retired positions. Normally my improved safety is turned down into its retired or inoperative position in which it is shown in Figs. 1 and 8. At this time its handle 8 is 95 entered into a transverse notch in the left hand side of the gun-stock which is not

shown. At this time, also, the segmental clearance-slot 20 of the rock-shaft 12 of the safety coincides, as shown in Fig. 8, with the curved wall of the transversely arranged locking-slot 29 formed in the rear end of the receiver 23 for the reception of the hub 21 of the bolt-handle 22 which is located at the rear end of the bolt 30 which has linear movement in the chamber 31 of the receiver.

10 When the safety is lifted from the retired position in which it is shown in Fig. 8, into its operative position in which it is shown in Fig. 7, its firing-pin retracting-cam 14 engages with the forward face of the flange 15 of the firing-pin retracting head 16 and positively cams back or retracts the firing-pin for a sufficient distance to entirely disengage its sear-notch 32 from the nose 33 of the sear 34, which latter is hung upon a pin 35 passing through its forward end and mounted in the receiver 23. The clearance-space 36 shown in Fig. 5, represents the above described rearward movement of the firing-pin under the action of the cam 14 of the safety.

15 25 A helical sear-spring 37 is arranged to exert a constant effort to lift the sear-nose 33 into position to engage with the sear-notch 32. The trigger 38 which is hung from the sear on a pin 39, is formed with an upstanding cam-like lug 40 which engages with the under face of the bolt 30 and acts as a fulcrum for depressing the rear end of the sear against the tension of its spring 37, so as to disengage its nose 33 from the sear-notch 32 and thus release the firing-pin 17 to the action of its spring 41.

30 35 The hub 21 of the bolt-handle 22 is formed with a combined handle-locking, recoil-taking and handle-guide lug 42 (Fig. 1) which, when the bolt-handle is in its elevated position, is entered into a longitudinal guide-slot 43 formed in the bottom of the tapering terminal 44 at the rear end of the receiver 23, the rear upper corner of which is cut away

40 45 downward and rearwardly to form the said terminal which is virtually separated from the body of the receiver by the transversely arranged locking-slot 29 receiving the hub 21 of the bolt-handle, which is held in its elevated position during the longitudinal movement of the bolt into its open and closed positions by the engagement of the said lug 42 with the side walls of the slot 43, this being the guide position of the said lug 42 of the hub 21 of the bolt-handle. On the other hand, when the bolt-handle is rocked from left to right, the rear face of the said lug 42 engages with the rear wall of the locking-slot 29 at a point to the left of the

50 55 60 65 axis of the bolt and in this position the said lug assists in taking the shock of recoil which is also taken by the rear face of the said handle-hub 21 which at the same time engages with the said rear wall of the slot at a point laterally opposite the engagement of

the lug 42 with the said wall, and on the right hand side of the axis of the bolt. The lug 42 has therefore handle-guiding and recoil-taking functions, dependent upon the position of the handle.

70

In addition to these two functions, the said lug 42 has a handle-locking function for which purpose it is formed in its outer edge with a locking-groove 45 which receives the slotted portion of the rock-shaft of the safety, as shown in Fig. 7, and thus positively locks the handle in its closed and locked position. This handle-locking function of the lug 42 is performed when the safety is lifted from its retired to its operative position after the handle has been rocked from left to right into its fully closed position. The safety in this position, locks the handle in its closed and locked position.

80

85 The operation of my improved safety is as follows: Assuming the gun to be cocked, as shown in Fig. 4, the sear-nose 33 will be engaged with the sear-notch 32 with the firing-pin spring 41 under tension. Now if the safety is raised by its handle 8 from its depressed or retired position as shown in Fig. 8, to its upstanding or operative position as shown in Fig. 7, its cam 14 will act upon the forward face of the annular flange 15 of the firing-pin-retracting head 16 and retract the firing-pin for a distance represented by the clearance-space 36 of Fig. 5, whereby the sear-notch 32 of the firing-pin will be entirely disengaged from the sear-nose 33. Meanwhile, as the safety swings from 90 its inoperative to its operative position, the clearance-notch 20 of its rock-shaft will be carried out of line with the rounded end of the guide-lug 42 and the adjacent uncut portion of the shaft will be entered into the 95 locking-groove 45 in the end of the lug, as shown in Fig. 7, whereby the safety operates to positively lock the bolt handle in the closed and locked position thereof. It will thus be seen that the safety not only operates to positively retract the firing-pin, but also to positively lock the bolt-handle in its recoil-taking position, whereby a double measure of safety is provided.

10

100 For the reception of the head 9 of the safety, the receiver 23 is formed in its left hand wall, with a transverse slot 46 producing a shoulder 47, preventing the rearward displacement of the safety which is assembled by first inserting its head 9 into the said slot 46 after which the rock-shaft is inserted into its axial bearing-hole in the receiver and pushed forward therein until its forward end is fully entered into the hole 10 in the said head 9. The head and shaft are 1 then pinned together by the pin 13.

11

When the firing-pin has been cammed back by the safety and is held thereby in its retired position, at which time the safety is also functioning as a positive lock for the 1

bolt-handle, it is impossible to fire the gun, since the control of the firing-pin is then entirely under the safety. At this time, the premature or accidental movement of the 5 sear by the trigger has no effect, and can have no effect on the firing-pin. I also wish to call attention to the fact that the gun is safe against premature firing during the throwing off of the safety, since by virtue of its 10 cam 14, the effect of turning the safety into its inoperative position is to gradually let the firing-pin forward until its sear-notch is brought into contact with the sear-nose. As herein shown the bolt-handle is solid 15 with the bolt which rotates as the handle turns, but my improved safety would operate in the same way if used in conjunction with a bolt-handle mounted to turn upon a 20 non-rotatable bolt, rotatable and non-rotatable bolts being well known in guns of the class to which my invention relates. I am aware that a safety having the same general purpose as the safety of my invention has heretofore been carried by the bolt itself, as 25 for instance, upon the U. S. Govt. rifle, mod. 1903. Such construction, however, requires a special form of bolt which in its adaptation to this form of safety is increased in weight, in size and expense and difficulty of 30 initial construction. These objections are avoided under my invention by actually mounting the safety in the receiver whereby I am enabled to dispense with forming a 35 bolt head upon the rear end of the bolt as has commonly been done heretofore. I do not, therefore, claim a safety for the purpose described but only a safety when actually mounted in the receiver in position to coact directly with the firing-pin installed within

the bolt and with the handle by which the 40 bolt is operated.

I claim:—

1. A bolt-action gun having a receiver having a guide-slot, a bolt, a bolt-handle provided with a guide-lug entering the said 45 guide-slot in the receiver, a firing-pin, a sear, and a safety axially mounted in the receiver and comprising a head having a cam to coact with the firing-pin for the retraction of the same and having a rock-shaft formed to 50 engage with the said guide-lug of the bolt-handle for locking the said handle in its closed position when the firing-pin has been retracted by the said cam.

2. A bolt-action gun having a receiver, a 55 bolt, a bolt-handle having a guide-lug formed in its end with a locking-groove, a firing-pin, a sear, and a safety axially mounted in the receiver and having a cam for retracting the firing-pin and a rock-shaft shaped to 60 enter the said locking-groove of the guide-lug for positively locking the handle in its closed and locked position.

3. A bolt-action gun having a receiver, a bolt, a bolt-handle having a guide-lug, a 65 firing-pin, and a safety having a cam for retracting the firing-pin and a rock-shaft formed with a clearance-slot to clear the said guide-lug and axially mounted in the receiver on opposite sides of the said clear- 70 ance-slot.

In testimony whereof, I have signed this specification in the presence of two subscribing witnesses.

FRANK F. BURTON.
